(57) **CLAIM**

The ornamental design for a desktop case as shown and described.

DESCRIPTION

FIG. 1 is a top view of a desktop case showing my new design;

FIG. 2 is a bottom view thereof;

FIG. 3 is a front view thereof;

FIG. 4 is a back view thereof;

FIG. 5 is a left-side view thereof;

FIG. 6 is a right-side view thereof;

FIG. 7 is a back left bottom perspective view thereof;

FIG. 8 is a back right top perspective view thereof;

FIG. 9 is a front right top view perspective thereof; and,

FIG. 10 is a front left top perspective view thereof.

The broken lines in the drawing represent portions of the desktop case that form no part of the claimed design.

1 Claim, 8 Drawing Sheets
